UNITED STATES PATENT OFFICE

CATHERINE A. HANSEN, OF OAKLAND, CALIFORNIA

DESIGN FOR A STOCKING PROTECTOR

Application filed October 4, 1930. Serial No. 37,137. Term of patent 3½ years.

To all whom it may concern:

Be it known that I, CATHERINE A. HANSEN, a subject of the King of Denmark, and a resident of Oakland, in the county of Alameda and State of California, have invented a new, original, and ornamental Design for a Stocking Protector, of which the following is a specification, reference being had to the accompanying drawing, forming part thereof.

I claim:

The ornamental design for a stocking protector substantially as shown.

CATHERINE A. HANSEN.
